(57) **CLAIM**

The ornamental design for a projector screen with an animated graphical user interface, as shown and described.

DESCRIPTION

FIG. 1 is a front view of a first embodiment of a projector screen with a first image of an animated graphical user interface showing our new design;

FIG. 2 is a second image thereof;
FIG. 3 is a third image thereof; and
FIG. 4 is a fourth image thereof.

FIG. 5 is a front view of a second embodiment of a projector screen with a first image of an animated graphical user interface showing our new design;
FIG. 6 is a second image thereof;
FIG. 7 is a third image thereof; and
FIG. 8 is a fourth image thereof.

FIG. 9 is a front view of a third embodiment of a projector screen with a first image of an animated graphical user interface showing our new design;
FIG. 10 is a second image thereof;
FIG. 11 is a third image thereof; and
FIG. 12 is a fourth image thereof.

FIG. 13 is a front view of a fourth embodiment of a projector screen with a first image of an animated graphical user interface showing our new design;
FIG. 14 is a second image thereof;
FIG. 15 is a third image thereof; and
FIG. 16 is a fourth image thereof.

FIG. 17 is a front view of a fifth embodiment of a projector screen with a first image of an animated graphical user interface showing our new design;
FIG. 18 is a second image thereof;
FIG. 19 is a third image thereof; and
FIG. 20 is a fourth image thereof.

FIG. 21 is a front view of a sixth embodiment of a projector screen with a first image of an animated graphical user interface showing our new design;
FIG. 22 is a second image thereof;
FIG. 23 is a third image thereof; and,
FIG. 24 is a fourth image thereof.

The subject matter of each of the first to sixth embodiments in this patent includes a process or period in which an image changes into another image. This process or period forms no part of the claimed design.

The outer broken lines showing a projector screen and the remaining broken lines showing portions of the graphical user interface form no part of the claimed design.
